[57] CLAIM

The ornamental design for enclosure for use primarily in a garden, as shown and described.

DESCRIPTION

FIG. 1 is a perspective view of an enclosure for use primarily in a garden showing my new design;
FIG. 2 is a side elevational view thereof, the opposite side elevational view being a mirror image of that shown;

FIG. 3 is a top plan view thereof;

FIG. 4 is a bottom plan view thereof;

FIG. 5 is a perspective view of an enclosure for use primarily in a garden showing a second embodiment;

FIG. 6 is a top plan view of FIG. 5.

FIG. 1.

FIG. 2.

FIG. 3.

FIG. 4.

FIG. 5.

FIG. 6.
